CUSHION DRIVE STARTER ATTACHMENT

Alex Johnson, Milwaukee, Wis., assignor of one-half to William H. Schmidt, Wauwatosa, Wis.

Application September 7, 1935, Serial No. 39,555

5 Claims. (CL. 74—7)

This invention appertains to starting attachments for internal combustion engines of the "Bendix" type, and has for one of its primary objects the provision of means whereby breakage of the starting shaft and associated parts is materially reduced or entirely eliminated.

One of the main objections to the "Bendix" starter is the fact that the cushioning springs and the starter shaft are subject to breakage due to the great stress placed thereon at the time of the starting of the engine.

It is, therefore, a salient object of my invention to provide novel means for reinforcing the starter shaft and for distributing the thrust placed thereon, whereby the possibility of the breaking of the shaft is reduced to a minimum.

Another important object of my invention is the provision of novel cushion blocks disposed between the starter shaft and the screw pinion shaft, whereby to entirely eliminate the use of the usual starter spring and at the same time effectively absorb and cushion the shock between the screw pinion and the starting shaft.

A still further object of my invention is to provide an improved engine starter of the above character which will be durable and efficient in use, one that will be simple and easy to manufacture, and one which can be placed upon the market and incorporated with an automobile at a low cost.

With these and other objects in view, the invention consists in the novel construction, arrangement, and formation of parts, as will be hereinafter more specifically described, claimed, and illustrated in the accompanying drawing, in which drawing:

Figure 1 is a fragmentary side elevation of my improved starter attachment, with parts thereof broken away and in section to illustrate structural details.

Figure 2 is a transverse section through my improved device, taken on the line 2—2 of Figure 1 looking in the direction of the arrows.

Figure 3 is a similar section, taken on the line 3—3 of Figure 1 looking in the direction of the arrows.

Referring to the drawing in detail, wherein similar reference characters designate corresponding parts throughout the several views, the letter S generally indicates my improved starting attachment for internal combustion engines, which includes the usual starting shaft 5.

This shaft 5 is driven from the starter motor 6 in any preferred manner. In accordance with my invention, I mount upon the starter shaft

5 an elongated hollow shaft 7, which serves as means for reinforcing the starter shaft. This hollow shaft 7 terminates short of the forward end of the starting shaft 5, and the forward end of the starting shaft 5 has rotatably mounted thereon the screw shaft 8 on which is mounted the starting pinion 9.

The shaft 8 and the starter pinion 9 can be of the general character employed in starting devices of this type, but it is to be noted that 10 the rear end of the screw shaft is piloted into the hollow shaft 7 and that the same is provided with an eccentric collar 10 forwardly of the hollow shaft.

Novel means is provided for connecting the 15 starting shaft and the screw shaft together, and this means includes a coupling member 11. The coupling member 11 includes an inner ring 12 and an outer ring 13. The ring 13 is materially longer than the ring 12, and the rings are rigidly 20 connected by a longitudinally extending connecting key rib 14.

The hollow shaft 7 is connected with the starting shaft 5 by means of a longitudinally extending key 15, and this key 15 has formed thereon a 25 longitudinally extending body plate 16. The plate extends radially beyond the hollow shaft and is diametrically disposed relative to the connecting key rib 14.

Confined between the rings 12 and 13 and interposed between the key rib 14 and the body plate 16 are substantially semicylindrical cushioning blocks 17 and 18. These blocks are preferably formed from live rubber and can be provided at spaced points with openings 19 which 35 tend to increase the resiliency of said blocks.

The cushioning blocks and the coupling member 11 can be surrounded by a casing sleeve 20, which serves as means for protecting my starting device.

By referring to the Figures 1 and 3, it will be noted that the eccentric collar 13 is fitted within the inner face of the forward ring 13, and this collar, the coupling device 11, and the casing sleeve 20 can be united by means of an adjusting screw 21.

In use of my improved device, when the starting motor 6 is set into operation and the pinion 9 is driven forwardly into meshing engagement with the teeth of the engine fly-wheel (not 50 shown), the shock will be effectively cushioned and taken up by the blocks 17 and 18, and the thrust will be uniformly distributed to the starting shaft 5.

When the coupling member 11 starts to rotate 55

due to its connection with the collar 13, the blocks 17 and 18 interpose between the key rib 14 and the body plate 16 and the same will tend to resume their normal positions as soon as the 5 thrust is released. By using the eccentric 10, thrust is materially reduced on the connecting screw 21.

Changes in details may be made without departing from the spirit or the scope of my invention, but what I claim as new is:

1. In an engine starting device, a starting shaft, a screw shaft having a pinion thereon, a coupling member on the starting shaft connected with the screw shaft including a pair of spaced rings disposed adjacent to the opposite ends of the starting shaft and a connecting key rib extending longitudinally of the starting shaft and free therefrom, a radial member carried by the starting shaft, and cushioning means between the coupling member and the radial member.

2. In an engine starting device, a starting shaft, a screw shaft, a coupling member on and free from the starting shaft connected with the screw shaft including a pair of spaced rings disposed adjacent to the opposite ends of the starting shaft and a connecting key rib, a radial member carried by the starting shaft and cushioning blocks confined between said rings and interposed between the key rib and the radial member.

3. In an engine starting device, a starting shaft, a hollow shaft surrounding the starting shaft, a screw shaft rotatably mounted on the starting shaft and piloted into said hollow shaft, a coupling member including a pair of spaced rings 35 rotatably fitted on the hollow shaft and on the screw shaft, and a connecting key rib, means connecting the coupling member and the screw shaft together, a key having a longitudinally extending body coupling the hollow and starter 40 shafts together, said body extending longitudinally of the hollow shaft and disposed substan-

tially diametrically opposite the connecting key rib, and resilient cushioning blocks surrounding the hollow shaft and disposed between the body and the connecting key rib.

4. In an engine starting device, a starting shaft, 5 a hollow shaft surrounding the starting shaft, a screw shaft rotatably mounted on the starting shaft and piloted in said hollow shaft, a coupling member including a pair of spaced rings, and a connecting key rib, one of said rings being mounted on the hollow shaft and the other on the screw shaft, said screw shaft having an eccentric portion fitted in the last mentioned ring, a key connecting the hollow and the starting shafts together, said key having a longitudinally extending body 15 extending radially of the hollow shaft, and semicircular resilient cushioning blocks disposed about the hollow shaft and confined between said rings and disposed between the key rib and said body.

5. In an engine starting device, a starting shaft, a hollow shaft surrounding the starting shaft, a screw shaft rotatably mounted on the starting shaft and piloted in said hollow shaft, a coupling member including a pair of spaced rings, 25 and a connecting key rib, one of said rings being mounted on the hollow shaft and the other on the screw shaft, said screw shaft having an eccentric portion fitted in the last mentioned ring, 30 a key connecting the hollow and the starting shafts together, said key having a longitudinally extending body extending radially of the hollow shaft, semicircular resilient cushioning blocks disposed about the hollow shaft and confined between said rings and disposed between the key rib and said body, a casing surrounding the body, coupling member, and cushioning blocks, and a pin connecting the casing, coupling member and screw shaft together.

ALEX JOHNSON.
